DENTIFRICE AND METHOD OF MAKING
SAME

Herl L. Crowther, Los Angeles, Calif.

No Drawing. Application January 3, 1934,
Serial No. 705,088

10 Claims. (Cl. 167—93)

My invention relates to the art of dental treatment and more particularly to dentifrices and the art of producing these.

Many different dentifrices for aiding the cleaning and preserving of the teeth have been marketed. These have been compounded uniformly on the theory that a clean tooth never decays. Accordingly, the only practical effect of these dentifrices has been for the most part to exercise a detergent, mildly scouring, and anti-septic action on the teeth and surrounding tissues.

Recently a condition of acid in the mouth has been discovered and it has been shown that these acids have a deteriorating effect upon the teeth. This discovery resulted in dentifrices generally having ingredients included in them which tend to chemically neutralize this acid condition.

I have found, however, that none of these pal-
liatives really eliminate the destructive action of
the acid in the mouth on the teeth, and it is ac-
cordingly an object of my invention to provide a
dentifrice which will actually prevent the decay
of teeth resulting from acid in the mouth.

In using previous dentifrices the effect of the
dentifrice was quite temporary in nature and
seldom continued longer than an hour after
using.

It is an object of my invention to provide a
dentifrice, the effect of which is comparatively
long-lived.

A still further object of my invention is to pro-
vide a dentifrice which will enhance the natural
beauty of the teeth as well as preserve this.

Yet another object of my invention is to pro-
vide a dentifrice, the normal, regular use of
which will cause to be applied to the exposed sur-
faces of the teeth a protective coating of some
relatively inert material, which will remain on
said surfaces a relatively long period of time and
which, while it remains, will protect such sur-
faces from attack by destructive agents present
in the mouth.

With the foregoing and other objects in view
which will become manifest in the following de-
scription, I have undertaken extensive experi-
ments to determine the conditions in the mouth
which have to do with decay of the teeth and
have discovered that the tooth structure is al-
ways susceptible to decay influences regardless of
whether or not it is cleaned even once or twice
a day. I have further discovered that the teeth
may be preserved against these influences by re-
placing the destructive film applied thereto by
the chemicals in the mouth by a protective coat-

ing of acid-resisting wax. In order to make this possible I have devised a dentifrice in which such a wax is incorporated, and this dentifrice and the method of producing the same constitutes the subject matter of this application. While numerous waxes might be used as an acid-resist-
ing wax in my dentifrice, ceresine has proved to be far superior to other waxes for this purpose. Accordingly, I shall describe my dentifrice as being compounded to include ceresine.

The dentifrice of my invention may be in the
form of a tooth powder or may be in the form of
a tooth paste. The powder form is preferable,
however, and for illustrative purposes I shall de-
scribe one way of compounding this.

To produce a seventy-five pound batch of this
powder the following ingredients are used:

Sodium perborate	16 lb. 6½ oz.
Magnesium oxide powder heavy	16 lb. 6½ oz.
Sodium bicarbonate	10 lb. 2½ oz.
Sodium chloride powder	10 lb. 2½ oz.
Calcium carbonate	4 lb. 4¾ oz.
Powdered borax	5 lb. 1¼ oz.
Powdered castile soap	8 lb. 3¼ oz.
Ceresine	25 oz.
Saccharin soluble	4 oz. 125½ grs.
Menthol	6 oz. 375 grs.
Thymol	2 oz. 250 grs.
Oil cloves	3½ oz.
Oil cassia	3½ oz.
Oil peppermint	4 oz. 205 min.
Oil spearmint	10 oz. 325 min.
Ether	64 oz. or 4 pts.

The manner of compounding my dentifrice in
powder form to embody the above ingredients is
as follows: All the solid materials are thoroughly
dried and are then sifted through a very fine
sieve, about No. 60, before mixing. These dry ma-
terials are then thoroughly mixed. The ceresine is
now melted. The oils, the menthol and the
thymol, are then mixed and this mixture is added
to the melted ceresine. The ceresine is now re-
moved from the fire and the ether is added there-
to. The mixture of ceresine, oils, and ether is now
incorporated with a quarter of the entire amount
of mixed powders by constantly stirring this
quantity of powder in a closed electrically heated
mixing machine, the powder, of course, being
stirred continuously during the spraying of the
liquid thereon and the machine remaining closed
during this mixing process.

When the powders and the liquids are thor-
oughly mixed the remaining three-quarters of
the powder is added thereto, the powder being

stirred continuously during this mixing process. When all the ingredients are now thoroughly mixed the cover is removed and the mixer is allowed to continue running for one hour while the 5 powder is maintained at a temperature which will drive away all the ether which was used to facilitate impregnating the powder with the ceresine.

Following the compounding of the dentifrice of my invention as above noted, the entire mixture 10 is then passed through a No. 40 sieve and placed in air-tight containers.

The powdered dentifrice of my invention when compounded as above described is used in the ordinary manner by brushing the teeth with this 15 powder. When this is done the cleansing ingredients of the powder remove the accumulated mucous from the surfaces of the teeth and for the time being neutralize the acid condition of the mouth. The solution of the water soluble 20 materials in the powder of course frees the wax and permits this to adhere to the surfaces of the teeth scrubbed by the brush. The wax thus applies a coating to the teeth so that following the brushing of the teeth with my dentifrice the 25 mouth feels remarkably clean and the teeth feel smooth. This is a result of the teeth being coated with ceresine which, as well known in the art, is a hard and strongly acid-resisting wax.

The coating of ceresine thus applied to the teeth 30 preserves the teeth from attack by the acids in the mouth during the period intervening between successive applications of the dentifrice of my invention. Furthermore, a high lustre is imparted to the teeth which greatly enhances their natural 35 beauty.

Should it be desired to make up the dentifrice of my invention in the form of a tooth paste instead of a powder as above described, the powdered dentifrice may be mixed with suitable 40 vehicles, such as glycerine and the like, to render the powder paste-like in consistency.

It is thus seen that I have provided a novel dentifrice and method of producing the same, this dentifrice providing a positive protection for the 45 teeth which endures over a considerable length of time after the application of the dentifrice and does not depend for any temporary neutralization of the chemical condition in the mouth for protecting the teeth from attack by the agents 50 so neutralized. A further advantage is found in the fact that the use of the dentifrice of my invention gives the teeth a beautiful polish which adds to their beauty as well as preserving them.

While for illustrative purposes I have hereinabove 55 described a specific mode of preparing the dentifrice of my invention, it is to be understood that my invention is by no means limited to this specific mode. For instance, an acid-resistant wax might be incorporated with any desired group 60 of the powdered ingredients mentioned or other powdered substances and when used would have certain of the novel and advantageous functions of the specific dentifrice described, and it is desired that the appended claims be construed with this in mind.

While ceresine has been found to be the best wax tried to date in the dentifrice of my invention, the scope of the invention is not to be understood as restricted to the use of this particular 70 wax. The essential functions of the wax in this dentifrice require only that the wax be capable of attenuation so as to form a thin protective coating upon exposed surfaces of the teeth when the latter are regularly brushed with the dentifrice, and that the wax be sufficiently resistant to 75

decomposition, erosion or melting under the physical and chemical conditions in the mouth, that this protective coating of wax remains on the teeth for at least several hours after its application. Where the term "wax" is used in the 5 claims, therefore, it is to be understood as restricted to those waxes having the characteristics pointed out hereinabove in this paragraph.

What I claim is:

1. In a dentifrice the combination of: a body 10 of dry powdered material suitable for introduction into the mouth without injury to the mouth membranes; and a sufficient quantity of wax impregnating the particles of said material and leaving said material in dry powdered form, to 15 form a thin protective coating of wax on the exposed surfaces of the teeth, when said teeth are brushed regularly with said dentifrice in the ordinary manner.

2. In a dentifrice the combination of: a body 20 of dry powdered material suitable for introduction into the mouth without injury to the mouth membranes and consisting principally of anti-septic and cleansing chemicals soluble in water; and a sufficient quantity of wax in a finely divided condition diffused throughout said material to form a thin protective coating of wax on the exposed surfaces of the teeth, when said teeth are brushed regularly with said dentifrice in the 25 ordinary manner.

3. In a dentifrice the combination of: a body 30 of dry powdered material suitable for introduction into the mouth without injury to the mouth membranes; and a sufficient quantity of ceresine impregnating the particles of said material and leaving said material in dry powdered form, to 35 form a thin protective coating of ceresine on the exposed surfaces of the teeth, when said teeth are brushed regularly with said dentifrice in the ordinary manner.

4. In a dentifrice the combination of: a body 40 of dry powdered material suitable for introduction into the mouth without injury to the mouth membranes and consisting principally of antiseptic and cleansing chemicals soluble in water; and a sufficient quantity of ceresine impregnating the particles of said material and leaving said material in dry powdered form, to form a thin protective coating of ceresine on the exposed surfaces of the teeth, when said teeth are brushed 50 regularly with said dentifrice in the ordinary manner.

5. In a dentifrice the combination of: a body 55 of cleansing material suitable for introduction into the mouth without injury to the mouth membranes; and a sufficient quantity of acid-resistant wax in finely divided condition and diffused throughout said cleansing material to form a thin protective coating of wax on the exposed surfaces of the teeth, when said teeth are brushed 60 regularly with said dentifrice in the ordinary manner.

6. In a dentifrice the combination of: a body 65 of cleansing material suitable for introduction into the mouth without injury to the mouth membranes; and a sufficient quantity of ceresine in finely divided condition and diffused throughout said cleansing material to form a thin protective coating of ceresine on the exposed surfaces of the teeth, when said teeth are brushed 70 regularly with said dentifrice in the ordinary manner.

7. In a dentifrice the combination of: a body 75 of cleansing material suitable for introduction into the mouth without injury to the membranes

thereof; a liquid vehicle mixed with said material to form a paste; and a sufficient quantity of finely divided acid-resistant wax diffused throughout said mixture to form a thin protective coating of 5 wax on the exposed surfaces of the teeth, when said teeth are brushed regularly with said dentifrice in the ordinary manner.

8. In a dentifrice the combination of: a body of cleansing material suitable for introduction 10 into the mouth without injury to the membranes thereof; a quantity of glycerine mixed with said material to form a paste; and a sufficient quantity of finely divided acid-resistant wax diffused throughout said mixture to form a thin protective coating of wax on the exposed surfaces of 15 the teeth, when said teeth are brushed regularly with said dentifrice in the ordinary manner.

9. In a dentifrice the combination of: a body of cleansing material suitable for introduction

into the mouth without injury to the membranes thereof; a liquid vehicle mixed with said material to form a paste; and a sufficient quantity of finely divided ceresine wax diffused throughout said mixture to form a thin protective coating of 5 wax on the exposed surfaces of the teeth, when said teeth are brushed regularly with said dentifrice in the ordinary manner.

10. In a dentifrice the combination of: a body of cleansing material suitable for introduction 10 into the mouth without injury to the membranes thereof; a quantity of glycerine mixed with said material to form a paste; and a sufficient quantity of finely divided ceresine wax diffused throughout said mixture to form a thin protective coating of wax on the exposed surfaces 15 of the teeth, when said teeth are brushed regularly with said dentifrice in the ordinary manner.

HERL L. CROWTHER.
